HOUSING FOR CEILING LIGHTING FIXTURE

William M. Johnson, Rte. 3,
Four Oaks, N.C. 27524

Filed Apr. 11, 1975, Ser. No. 567,186

Term of patent 14 years

Int. Cl. D26—05

U.S. Cl. D48—23 R

FIG. 1

FIG. 2

FIG. 3

FIG. 4

FIG. 5

FIG. 1 is a perspective view of a housing for ceiling lighting fixture showing my new design as seen from below;

FIG. 2 is a perspective view thereof as seen from below and from the opposite side of FIG. 1;

FIG. 3 is a perspective view as seen from above;

FIG. 4 is an inverted side elevational view thereof, the opposite side being identical; and

FIG. 5 is an inverted end elevational view thereof, the opposite end being identical.

I claim:

The ornamental design for a housing for ceiling lighting fixture, as shown and described.
